UNITED STATES PATENT OFFICE.

ALBERT T. GOOKIN, OF CAMBRIDGE, MASSACHUSETTS.

GUARD AND SIGNAL FOR RAILWAYS, ETC.

Application filed October 6, 1921. Serial No. 505,822.

To all whom it may concern:

Be it known that I, ALBERT T. GOOKIN, a citizen of the United States, and a resident of Cambridge, in the county of Middlesex and State of Massachusetts, have invented a new and Improved Guard and Signal for Railways, Etc., of which the following is a description.

My invention relates to a guard and signal for highways, grade crossings, bridges, etc., to afford warning especially for drivers of vehicles and to offer a barrier to the passage of a vehicle over the crossing when the signal is displayed. A contemplated use 10 of the guard also is to enable police and law officers to prevent the escape from a city or town of a vehicle being sought by the officers.

Objects of my invention are to provide a 20 guard and signal of the indicated character improved in various particulars to the end whereby, among other advantages, the guard is made so as to yield to the impact of a vehicle to minimize the possibility of injury to 25 the guard and to the vehicle, as well as to provide for the removal of a section of the guard without affecting the functions of the remaining sections and enabling the damaged section to be replaced with facility.

Reference is to be had to the accompanying drawings forming a part of this specification, it being understood that the drawings are merely illustrative of one example 30 of the invention.

Figure 1 is a plan view of a crossing embodying an installation of my improved guard and signal;

Figure 2 is a vertical section on the line 2-2, Figure 1;

Figure 3 is a vertical section on the line 3-3, Figure 2;

Figure 4 is a detail in elevation showing the yieldable means for raising and lowering the guard sections;

Figure 5 is a vertical section on the line 5-5, Figure 4.

In the particular installation of my invention are illustrated crossing rails 10, 10^a and the bed 11 is made substantially level 50 with the rails, there being grooves 12 between the rails and bed for the passage of the flanges of car wheels, the numeral 13 indicating the intersection of the rails.

In accordance with my invention I pro- 55 vide series of guard sections 14, 14^a, the lat-

ter sections being smaller and disposed between the rails of the track. Said sections are secured by hinges 15, the character 15^a indicating the strap of each hinge secured to the bed 11 or to a part appurtenant to the 60 bed.

Signal towers 16 are provided, preferably four in number, at the outer corners of the crossing and provided with semaphores 17. The upper portions of the towers with the 65 semaphores simulate a traffic officer and his arms.

Illustrated means for operating the signals and raising and lowering the guard sections 14 comprises a shaft 18 at one side of the crossing extending beneath one series of rails. On the said shaft 18 are clamps 19 secured by bolts 19^a or the like to permit of their ready removal from the shaft when required. The clamps 19 are arranged in 70 pairs and from the clamps of each pair I extend spring bars 20 joined by a cross head 21 slotted at its ends to engage the edges of parallel plates 22 on the under side of each guard section 14. The arrangement is such 75 that with the rocking of the shaft 18 the clamps 19 will turn therewith through an arc to cause the head 21 to raise the sections 14, said heads 21 having sliding engagement with the guard sections. With the guard 80 sections 14 raised to constitute a barrier to a vehicle proceeding over the crossing, should a vehicle strike the guard, said guard will yield by reason of the resiliency of the spring bars 20, thereby reducing the possibility of 85 damage to the guard sections and to the vehicle. The bolts or the like 19^a and the hinges 15, 15^a permit of the removal or renewal of a guard section 14 and its operating means comprising the elements 19, 90 20, 21.

In order to operate the semaphores 17 with the raising and lowering of the guard sections 14, suitable means is provided establishing an operative connection between 100 the shaft 18 and said semaphores. In the illustrated example there is provided on the shaft 18 quadrants 23 adapted to rock with the shaft. To establish connection between the elements 23 and the semaphore arms 17, 105 I have shown cables or flexible elements 24 secured at one end to the elements 23 and branching as at 25 at their upper ends, the branches being secured to the semaphore arms 17 of a pair. To turn the shaft 18 110

there is shown a hand lever 26 fixed on a rock shaft 27 on which is a pinion 28 meshing with a gear wheel 29 on shaft 18. On the shaft 18 also is a bevel pinion 31 meshing with a similar pinion 32 on a shaft 33 disposed at right angles or approximately so to the shaft 18 and extending to the opposite side of the crossing, said shaft 33 at the said opposite side of the crossing carrying a fixed 10 bevel pinion 32^a, meshing with a pinion 31^a on a shaft 18^a parallel with the shaft 18 at the opposite side of the crossing, the shaft 18^a having quadrants 23^a to which is secured flexible elements 24^a rising in the towers 16^a 15 at the adjacent side of the crossing, said towers having semaphores 17^a to which the branches 25^a of cables 24^a connect. Thus, the semaphores at the four corners of the crossing will be simultaneously operated and 20 the guards 14, 14^a at two opposite sides of the crossing will simultaneously be raised or lowered.

I would state in conclusion that while the 25 illustrated example constitutes a practical embodiment of my invention, I do not limit myself strictly to the exact details herein illustrated, since, manifestly the same can be considerably varied without departure from the spirit of the invention as defined 30 in the appended claims.

Having thus described my invention, I claim:

1. In a road guard of the class described, a barrier comprising separate sections 35 hinged adjacent the road surface to be manually raised or lowered, and yieldable means mounted on a shaft in sliding contact with

said barrier for raising the same and afford a recoil to the barrier when impacted.

2. In a guard of the class described, a barrier comprising separate sections hinged to be given a raised or a lowered position, a rock shaft, a raising and lowering head for each guard section, spring means sustaining said head, and means to detachably clamp 45 said spring means to said shaft.

3. In a guard of the class described, a barrier comprising separate sections hinged to be raised or lowered, an operating revolute shaft for said sections and separate resilient means on said shaft slidably engaging the separate sections to raise or lower the same.

4. In a guard of the character described, a plurality of barriers extending adjacent 55 the surface of a road, a shaft rockably arranged beneath the barriers, spring actuated means connected between the shaft and the barriers to operate the latter by rocking the former, and allow the barriers to yield to 60 an impact.

5. In a guard of the class described, a series of barriers arranged adjacent and normally lying flush with a pavement of a road, a shaft arranged beneath the barriers 65 and crosswise to the road, crank means adjacent one end of said shaft and gear means between the crank means and the shaft for rocking the latter; together with resilient means in contact with the under surface of 70 the barriers for raising the same and afford a recoil therefor when impacted.

ALBERT T. GOOKIN.
